US0D1107215S

(12) **United States Design Patent** (10) **Patent No.:** **US D1,107,215 S**
(45) **Date of Patent:** **** Dec. 23, 2025**

(54) **ORAL PRODUCT**

(71) Applicant: **Church & Dwight Co., Inc.**, Princeton, NJ (US)

(72) Inventors: **Christopher Wells**, Hamilton, NJ (US); **Theresa Delahanty**, Washington Crossing, PA (US); **Pamela Dozier**, Doylestown, PA (US); **Ryan Langeveld**, Wall, NJ (US)

(73) Assignee: **Church & Dwight Co., Inc.**, Princeton, NJ (US)

(**) Term: **15 Years**

(21) Appl. No.: **29/839,983**

(22) Filed: **May 25, 2022**

(51) **LOC (15) Cl.** **28-01**

(52) **U.S. Cl.**

USPC **D24/101**; D1/114

(57) **CLAIM**

The ornamental design for an oral product as shown and described.

DESCRIPTION

FIG. 1 is a top perspective view of an oral product showing our new design;

FIG. 2 is a bottom perspective view thereof;

FIG. 3 is a top view thereof;

FIG. 4 is a bottom view thereof;

FIG. 5 is a left side view thereof;

FIG. 6 is a right side view thereof;

FIG. 7 is a front view thereof; and,

(Continued)

FIG. 8 is a rear view thereof.

1 Claim, 6 Drawing Sheets
